UNITED STATES PATENT OFFICE.

JOSEPH R. BOWLING, OF ST. LOUIS, MISSOURI, ASSIGNOR TO THE IN-
GOLDSBY AUTOMATIC CAR COMPANY, OF ST. LOUIS, MISSOURI, A
CORPORATION OF WEST VIRGINIA.

CAR SIDE.

SPECIFICATION forming part of Letters Patent No. 788,627, dated May 2, 1905.

Application filed January 25, 1904. Serial No. 190,426.

To all whom it may concern:

Be it known that I, JOSEPH R. BOWLING, a citizen of the United States, residing at St. Louis, State of Missouri, have invented a certain new and useful Improvement in Car Sides, of which the following is a full, clear, and exact description, reference being had to the accompanying drawings.

My invention relates to the construction of car sides, and has for its object the strengthening of such sides whereby they may be enabled to carry a large proportion of the load without unduly increasing the weight of the same.

Generally speaking, the invention may be defined as consisting of the combinations of elements set forth in the claims hereto annexed.

Referring to the drawings, Figure 1 represents a side elevation of a car side embodying my invention. Fig. 2 represents a side elevation of a portion of a car side, showing a modification of the end construction illustrated in Fig. 1. Fig. 3 represents a detail in elevation of one of the end tie-rods. Figs. 4 and 5 are detail views representing different forms of washers.

A represents one of the sides of the car, the same comprising an upper chord B, a lower chord B', end posts C, and intermediate posts C', C, and C³, connecting said chords, and planks D, suitably secured to the inner sides of said posts. Vertical posts C⁴ extend from the bolsters E inside of the planks D to the cross-caps at the ends of the car-body.

F represents the end sills.

G represents diagonal tie-rods extending from the upper face of the upper chord to the lower face of the lower chord, said rods being inclined downwardly toward the center of the car. As shown, these rods extend from the junctions of the vertical posts C² C⁴ with the upper chord to the junctions of such post with the lower chord, said rods extending through the chords and being provided with inclined washers g g' g². Suitable nuts g³ are provided by means of which the tension of said rods may be adjusted, the rods being free from the sides to permit such adjustment.

The lower ends of the two innermost tie-rods G extend to the lower central portion of the car side beneath a central post C³.

Through the chords B B' and the post C³ at the center of the car extends the tie-rod G', the purpose of which is to prevent that portion of the chord B between the upper extremities of the innermost tie-rods G from buckling upward as the resultant of the strains set up by said rods in said chord.

It will be noted from an inspection of the drawings that the point where the lower end of one tie-rod G passes through the lower chord and the point where the upper end of the tie-rod next remote from the end of the car passes through the upper chord are in substantial vertical alinement, said points being connected by the vertical posts C². I have shown vertical posts intermediate of the upper and lower extremities of each tie-rod. These posts are merely for the purpose of stiffening and securing the planks D and may be entirely omitted, if desired, without materially weakening the construction of the car side.

The construction above described constitutes, in effect, a Pratt truss applied to the car side. Of the truss the chord B and the vertical posts constitute the compression member, while the bottom chord B' and the tie-rods constitute the tension member. The intermediate planks D being securely bolted to the posts will act in the capacity of counters to overcome whatever unequal loading is general to railway car-service. If, however, such planks should prove inadequate for this purpose, counter tie-rods may be introduced running from the top of the post C³ to the bottom of the posts C².

The lower extremities of the innermost tie-rods G may be provided with a common bearing or washer plate g⁴. The ends of the plate are bent back upon said plate to form the inclined washers g'. The tie-rod G' may extend through this plate intermediate of the washers.

As a simple manner of overcoming the difficulty of having the tie-rods G² at the ends

of the car and the tie-rods G cross each other at their upper ends and to avoid the large amount of cutting of the top member incident thereto I have formed the members G² as shown 5 more particularly in Fig. 3. The upper end of the rod is flattened into a plate, a portion of said plate being inclined to form a washer or bearing surface g³ for the nut of the tie-rod G. The lower end of the tie-rod G² extends through the end sill F and is provided 10 with a washer and a nut.

In Fig. 2 I have shown a modification of the end of the car side shown in Fig. 1, the inclined post C being done away with and a 15 vertical post C⁵, extending from the bolster to the cross-cap, being substituted therefor.

In Fig. 4 I have shown another modification of the construction employed for the end of the car side. This construction is similar 20 to that shown in Fig. 2 in that I retain the vertical post C⁶ shown in Fig. 2, but differs from the construction shown in such figure in that the tie-rod connecting the members B E' is of the ordinary construction and in 25 place of the bearing-plate formed with said rod I employ a separate plate g⁶, said plate having a vertical flange g⁷, engaging the end of the member B, and a horizontal flange g⁸, resting on the top of said member. The end 30 of this horizontal flange is turned back upon the body of the flange, as shown at g⁹, to form an abutment for the washer g¹⁰, said washer being cut away and provided with an overhanging lip g¹¹, passing over the top of 35 the folded portion g⁹ of the plate g⁶. The tie-rod G³ passes through the horizontal portion of the plate g⁶ and is provided with a nut for adjusting the tension of the same.

The washers g g² and the plates formed with 40 the rods G² are provided with lugs g¹² g¹³ g¹⁴, respectively engaging the members B B', whereby said washers and plate are held securely in place. As a modification of this construction I may employ the washers g¹⁵. 45 (Shown in Fig. 5.) These washers are provided with a number of angular projections g¹⁶, which in setting up the nuts on the ends of the rods G will be pressed into the members B B', and thus prevent the slipping of said 50 washers.

While I have shown but two tie-rods G G' on each side of the center of the car and while such tie-rods are shown as extending from the top of one post to the bottom of the second post therefrom, it will be evident that as occasion 55 may demand—as, for instance, increasing the length or decreasing the depth of the car side—the intermediate post may be omitted and the tie-rods extend from the top of one post to 60 the bottom of the next adjacent post and that the number of such tie-rods and posts may be increased to accommodate the increased demand on the side. While I have shown the rods located exteriorly of the planks D, it will

be evident that said posts and rods may be 65 located interiorly of said planks without affecting the spirit of my invention.

What I claim as my invention, and desire to secure by Letters Patent, is—

1. In a trussed car side, the combination of 70 upper and lower chords, a central vertical post, end posts, and a post intermediate of said center and end posts on each side of the center of the car side, said posts extending between said chords, of inclined tie-rods free 75 from the sides and extending from the junction of each of the end posts and an upper chord to the junction of the intermediate posts and the lower chord, inclined tie-rods extending from the junction of said intermediate 80 posts and the upper chord to the junction of the central post and the lower chord, and means for adjusting the tension of said rods, substantially as described.

2. In combination with the side of a car, upper 85 and lower members, a tie-rod connecting the ends of said members, and an additional tie-rod extending from the end of the upper member to the lower member and connected thereto at a point intermediate of the end and 90 center of the said member, substantially as described.

3. In combination with the side of a car, upper 95 and lower members, a tie-rod connecting the ends of the members, said rod being flattened at the upper end to form an inclined bearing or washer surface, an inclined tie-rod extending through and at substantially right angles to the inclined portion of the first tie-rod and provided with a nut bearing against 100 said washer, the lower end of said second tie-rod extending through and being connected to the lower member, substantially as described.

4. In a car side, the combination of upper 105 and lower members, a bearing or washer plate for the end of the upper member, said plate having a portion engaging the end of the upper member and a portion engaging the upper surface of said member, the end of the latter portion being folded back upon itself to form 110 an abutment, an inclined tie-rod extending through the horizontal portion and engaging said upper and lower members, and a washer on the upper end of said tie-rod, said washer abutting against the folded portion of the 115 plate, substantially as described.

5. In a car side, the combination of upper 120 and lower members, a bearing-plate having a portion adapted to engage the end of the upper member and a portion adapted to engage 125 the upper surface of said member, the end of the portion of the bearing-plate which engages the upper surface of said member being folded back to form an abutment, an inclined tie-rod extending through the upper surface of said plate and connecting said members, said tie-rod having a washer on the upper end of the same, said washer being pro-

vided with an overhanging lip and a vertical abutment beneath said lip adapted to engage the abutment on the plate, substantially as described.

5 6. In a trussed car side, the combination of upper and lower members, a central vertical post connecting said members, inclined tie-rods extending from the upper member through the portion of the lower member adjacent to said post, a plate on the lower side of said lower member adjacent to said post, and means for adjustably securing said tie-rods to said plate, substantially as described.

15 7. In a car side, the combination of upper and lower members, a central vertical post connecting said members, tie-rods extending between the upper and lower members and inclined downwardly toward the center of the side on each side of said post, the rods adjacent to said post extending substantially beneath the same, and means for adjusting the tension of said rods, substantially as described.

25 8. In a car side, the combination of upper and lower members, a central vertical post connecting said members, tie-rods on each side of said central post and extending through said members and inclined downwardly toward the center of the car, the rods adjacent to said central post extending beneath the same, a central tie-rod extending through said members, and means for adjusting the

tension of the said rods, substantially as described.

9. In a car side, the combination of upper and lower members, a central vertical post 35 connecting said members, tie-rods extending through said members and inclined from the upper member downwardly toward the center of the car, the tie-rods adjacent to said central post extending substantially beneath the same, 40 a vertical tie-rod extending through said members and through the central post, and means for adjusting the tension of said rods, substantially as described.

10. In a car side, the combination of upper 45 and lower members, a central vertical post connecting said members, a bearing-plate beneath said post having inclined bearing-surfaces and an intermediate flat surface, inclined rods extending from the upper member through the lower member and the inclined bearing-surfaces on said plate, a vertical tie-rod extending through said members and the intermediate flat surface of said plate, and nuts for adjusting the tension of said 50 rods, substantially as described.

In witness whereof I hereunto affix my signature in the presence of two witnesses.

JOSEPH R. BOWLING.
